PORTABLE EXPANDABLE CAMPING GRILL

James E. Hemphill, 1200 Ruth St.,
Austin, Tex. 78757

Filed Nov. 29, 1974, Ser. No. 528,267

Term of patent 14 years

Int. Cl. D7—02

U.S. Cl. D7—136

FIG. 1

FIG. 2

FIG. 1 is a top plan view for a portable expandable camping grill showing my new design; and

FIG. 2 is a perspective view thereof.

The bottom of the portable expandable camping grill is a mirror image of the top view shown in FIG. 1.

I claim:

The ornamental design for a portable expandable camping grill, substantially as shown and described.
